No. 739,710.

PATENTED SEPT. 22, 1903.

C. PERILLAT.
INCANDESCENT HYDROCARBON LAMP.

APPLICATION FILED MAY 26, 1900.

NO MODEL.

UNITED STATES PATENT OFFICE.

CHARLES PERILLAT, OF BOSTON, MASSACHUSETTS, ASSIGNOR TO KITSON HYDROCARBON HEATING AND INCANDESCENT LIGHTING COMPANY, OF PHILADELPHIA, PENNSYLVANIA, A CORPORATION OF WEST VIRGINIA.

INCANDESCENT HYDROCARBON-LAMP.

SPECIFICATION forming part of Letters Patent No. 739,710, dated September 22, 1903.

Application filed May 26, 1900. Serial No. 18,089. (No model.)

To all whom it may concern:

Be it known that I, CHARLES PERILLAT, a citizen of France, residing in Boston, in the county of Suffolk and State of Massachusetts, have invented an Improvement in Single-Mantle Incandescent Hydrocarbon-Lamps, of which the following description, in connection with the accompanying drawings, is a specification, like characters on the drawings representing like parts.

This invention relates to an incandescent oil-lamp of that class known as "single-mantle" lamps.

This invention has for its object to provide a single-mantle lamp in which the vaporizer is uniformly heated to the desired or proper heat to prevent the formation of carbon and clogging up of the vaporizer, which would occur if the vaporizer is permitted to become too hot, or to prevent an improper vaporizing of the oil, which would occur if the vaporizer is allowed to become too cold, and these results are obtained by providing a construction in which the vaporizer is heated with a reduced or small flame which is sufficient to maintain the vaporizer heated to the proper temperature to vaporize the oil, while the mantle is supplied with an increased volume of vapor and air in an indirect manner, as will be described.

Another feature of the invention consists in providing novel means, as will be described, for simultaneously operating the needle-valve and oil-valve in the same direction and in providing means whereby these valves are locked or held against displacement by the pressure of the oil employed in connection with the lamp.

These and other features of this invention will be pointed out in the claims at the end of this specification.

Figure 1 is a vertical section and elevation of a single-mantle incandescent hydrocarbon-lamp embodying this invention; Fig. 2, a transverse section on the line 2 2, Fig. 1, looking down; Fig. 3, a detail in plan to be referred to; Fig. 4, a vertical sectional detail of the oil and needle valves; Fig. 5, a modification to be referred to; and Fig. 6, a

sectional detail on the line 6 6, Fig. 4, to be referred to.

The lamp herein shown as embodying this invention is provided with a burner composed of a plurality of concentric tubes, herein shown as four in number and marked *a b c d*, which are united or secured together to form a single structure by means of radially-extended tubes *e*, preferably three in number and which serve as air-supply tubes for the burner.

The tubes *a b* coöperate to form a chamber *f*, provided with top and bottom walls *g h* and with vapor-outlets *i* near the lower end of the said chamber. The vapor-outlets *i* may and preferably will be made as a plurality of holes arranged about the circumference of the tube *b* and lead into a chamber *j*, formed by the tubes *b c*, the said chamber having top and bottom walls *k m* and preferably provided, as herein shown, with two sets of vapor-outlets *n o*, formed in the tube *b* above the top wall *g* and bottom wall *h* of the chamber *f*. The openings *n* are made substantially large and are disposed about the circumference of the tube *b* and lead into a chamber *p*, formed in the upper part of the tube *b* by the partition-wall *g* and a cap *q* of foraminous material. The openings *o* are made smaller than the openings *n*, as their function is to supply only sufficient vapor to insure the proper heating of the vaporizer, which is preferably made as herein shown and consists of a tube *2*, fitted onto the threaded nipple *3* of a valve-fitting *4*, adapted to be connected to a fitting *5*, attached to a gas-burner *6*, as shown in Fig. 1, or the valve-fitting may be connected to a font *7*, containing oil and air under pressure. (See Fig. 5.) The vaporizing-tube *2* at its upper end is provided with an annular flange *8*, through which are made a plurality of holes or openings *9* for supplying air to the flame issuing from the small vapor-outlets *o*, and below the flange *8* the vaporizing-tube is provided with a second flange *10*, which is of substantially the same size as the flange *8* and is separated therefrom by an air-space *12*, the flange *10* acting as a shield for the heating-jet. The vaporizing-tube extends up into

the inner tube *a* and its upper surface is substantially on a line with the air-supply tubes *e*, so that the vapor issuing from the vaporizer through a substantially small or minute opening in the upper surface of the tube *2* may be commingled with the air drawn in through the supply-tubes *e*. The mixture of air and vapor passes up through the tube *a* into the chamber *f*, and the upwardly-moving mixture of vapor and air is arrested by the wall *g* and caused to pass down said chamber outside of the tube *a* and into the chamber *j* through the outlet-openings *i*. The mixture of air and vapor fills the chamber *j*, and the larger quantity or greater volume passes up the chamber *j* and out therefrom through the openings *n* into the chamber *p*, from which it passes through the foraminous cap *q* and is ignited, thus raising to incandescence a mantle *t*, supported above and in line with the outlet-mouth of the burner. A smaller volume or portion of the mixture of air and vapor passes from the lower end of the chamber *j* through the outlets or openings *o*, and, being ignited, forms a heating-jet, which surrounds the upper portion of the vaporizer, thus heating the same sufficiently to insure proper vaporization of the oil in the vaporizing-tube.

Owing to the proximity of the small vapor-outlets *o* to the vapor-inlet openings *i* for the chamber *j*, the supply of vapor for the heating-jet is assured and liability of the heating-jet being extinguished before the main flame is extinguished is avoided, thus obviating the danger of fires caused by the heating-jet being extinguished by a deficient supply of vapor to maintain it, thereby cooling the vaporizer and allowing the oil to be forced up into contact with the hot mantle.

The supply of vapor to the burner is controlled by a needle-valve *20*, having its lower end attached to the oil-valve *21*, so that both valves may be moved simultaneously in the same direction. The oil-valve *21* is made tapering at its upper end and co-operates with the outlet-passage *22* for the valve-chamber *23*, (see Fig. 4,) and the said valves may be actuated, as shown, by a pin *25*, extended into an opening *26* in the valve *21* and attached to a valve-stem or actuating-rod *27*, which is extended into the valve-fitting *4* substantially at right angles to the movement of the valve *21*, the said rod or stem being supported by a sleeve *28*, attached to the valve-fitting and provided with a packing-nut *30* at its outer end. The needle-valve *20* may and preferably will be screw-threaded at its lower end to engage a screw-threaded socket in the end of the oil-valve *21*, which construction permits the needle-valve to be adjusted with relation to the discharge-orifice in the vaporizer, so that the oil-valve may be closed without bringing the needle-valve into contact with the walls of the discharge-orifice of the vaporizer, thus avoiding the discharge-orifice being enlarged by the needle-valve when the oil-supply to the

vaporizer is shut off, while at the same time permitting the discharge of vapor to be regulated.

One of the features of this invention consists in preventing the oil-valve being moved by the pressure of the oil, which if permitted to take place would seat the valve and shut off the supply of vapor to the burner, and this result is accomplished, as herein shown, by providing the valve-actuating rod or stem *27* with screw-threads *32* at its inner end, (see dotted lines Fig. 4 and full lines Fig. 6,) which engage a threaded socket *33*, extended into the valve-fitting from one side of the valve-chamber *23*. By an inspection of Fig. 4 it will be seen that the oil-valve, which is moved by the pin *25* on the rod or stem *27*, is locked against longitudinal movement except when actuated by the rotary movement of the rod or stem *27*, as the movement of the valve is in a direction transverse to the said stem or rod, which is given only a half-turn in opposite directions to close and open the oil and needle valves. The oil-valve *21* is made a little smaller in diameter than the valve-chamber for the passage of oil to the vaporizer when the valve is open.

The single-mantle lamp herein shown may receive its supply of oil from the font *7*, (see Fig. 5,) containing oil and air under pressure, or it may receive its oil from a pipe *34*, connected with a supply-tank (not shown) and may be supported upon the gas-fixture *6*, as shown in Fig. 1, in which case the gas may be utilized for heating the vaporizer in starting the lamp. For this purpose the fitting *5* is provided with an oil-passage *40* and with a gas-passage *41*, with which latter connects a pipe *42*, having its upper end encircled about the vaporizer and provided with gas-outlet perforations *43*.

I prefer to make the gas-outlets *o* for the heating-jet in the tube *b* below the wall *h*; but they may be made in the wall *h* instead, and while this latter construction is good I do not deem it as efficient as the construction shown.

The tube *d* forms a wind-shield for the heating-jet and a chimney for the flame from the alcohol-cup *35* when the latter is used for starting the lamp.

By reference to Fig. 1 it will be seen that the vapor issuing from the vaporizer is commingled with fresh air near the discharge-orifice of said vaporizer and that this mixture is caused to pass through a series of chambers before it finally reaches the point where it is consumed, and as a result the said mixture is commingled in a most efficient manner, which serves to insure a proper combustion, and thus increases the efficiency of a lamp of this class. The mantle *t* may be supported above and in line with the outlet-mouth of the burner, as herein shown, by a rod or arm *50*, adjustably secured by set-screw *51* to a stud or arm *52* on a ring or collar *53*, fitted over the upper portion of the

tube b. The irregular course through which the vapor passes on its way through the burner acts to deaden the sound, so that noise is reduced to a minimum, which is very desirable in lamps of this character.

5 I claim—

1. In a lamp of the class described, the combination with a vaporizer provided with an oil-inlet at its lower end and with a vapor-outlet at its upper end, and a valve-fitting connected with said vaporizer, of an oil-valve in said fitting provided with an opening in its body, a needle-valve in the vaporizer positively attached to said oil-valve, a rotatable rod or stem extended laterally through said valve-fitting, and means projecting from said rod or stem into the opening in the oil-valve to effect movement of both of said valves simultaneously in the same direction when the 15 said rod or stem is rotated in either direction, substantially as described.

2. In a lamp of the class described, the combination with a vaporizer provided with an oil-inlet at its lower end and with a vapor-outlet at its upper end, and a valve-fitting connected with said vaporizer, of an oil-valve in said fitting, a needle-valve in the vaporizer positively attached to said oil-valve to move therewith, a rotary actuating device engaging 25 said oil-valve and extended laterally with relation thereto, and means on the rotary actuating device in engagement with the valve-fitting to prevent said oil-valve being moved by pressure of the oil, substantially as described.

3. In a lamp of the class described, the combination with a vaporizing-tube provided with a vapor-outlet at its upper end and with an oil-inlet at its lower end, a valve-fitting to 30 which said vaporizer is attached and having an oil-passage and a valve therein, a gas-pipe, a fitting fixed on said gas-pipe and to which said valve-fitting is secured, said pipe-fitting being provided with a passage for oil for the 35 said valve-fitting and with a separate passage for gas, and a tube or pipe communicating with said gas-passage and having its upper end arranged in close proximity to the said vaporizing-tube and provided with a gas-outlet, substantially as described.

4. In a lamp of the class described, a burner composed of an inner tube, an outer tube closed at its top and bottom, and an intermediate tube provided with a partition-wall 40 above the inner tube and forming chambers within the intermediate tube and with a partition-wall forming the bottom of the lower one of said chambers, said intermediate tube having openings in it above and below the 45 upper one of said partition-walls to connect the said chambers with the chamber formed by the outer and intermediate tubes, and having auxiliary openings below the lower one of said partition-walls to connect the chamber formed by the outer and intermediate tubes with the interior of the intermediate tube, for the purpose specified.

5. In a lamp of the class described, a burner composed of an inner tube, an outer tube closed at its top and bottom, and an intermediate tube forming chambers with the said inner and outer tubes and provided with a partition-wall above the inner tube which separates the intermediate tube into two chambers and with a partition-wall forming the bottom of the lower one of said chambers, said intermediate tube having openings in it above and below the upper one of said partition-walls to connect the separate chambers in the inner tube with the chamber formed by the intermediate and outer tubes, and having auxiliary openings below the lower one of said partition-walls communicating with the chamber between the outer and intermediate tubes, and air-supply tubes extended transversely through the outer, intermediate and inner tubes, substantially as described.

6. In a lamp of the class described, a burner composed of an inner tube, an outer tube provided at its top and bottom with end walls, and an intermediate tube provided with a partition-wall above the inner tube forming two chambers, said intermediate tube having openings to effect communication between the chambers of the intermediate tube and the chamber formed by said intermediate and outer tubes, and an air-supply tube extended across the said burner-tubes, substantially as described.

7. In a lamp of the class described, the combination with a vaporizer, of a burner provided with an inner tube, a tube surrounding the said inner tube and provided with a bottom wall and with a wall above the inner tube but below the upper edge of said surrounding tube to form two chambers therein, and means for connecting the lower portion of the lower chamber with the upper chamber, and an air-supply tube extended across the burner-tubes, substantially as and for the purpose specified.

8. In a lamp of the class described, the combination with a vaporizer provided with an oil-inlet at its lower end and with a vapor-outlet at its upper end, and a valve-fitting connected with said vaporizer and provided with a screw-threaded socket, of an oil-valve in said fitting, a needle-valve in the vaporizer connected with said oil-valve to move simultaneously therewith, a rotary valve-stem extended laterally with relation to the said oil-valve and provided with means for engaging said valve and with screw-threads to engage the threaded socket in the valve-fitting, whereby the oil-valve is prevented from being closed by the pressure of the oil, substantially as described.

9. A vaporizing-burner comprising a casing, a tube therein having perforations communicating with the upper and lower portions of the chamber formed in the casing, said tube being further provided with a diaphragm located between said series of openings, a perforated plate in the base of said tube, a

mixing-tube disposed within said tube and having air-intakes, and a vaporizing-tube disposed within said perforated tube below said mixing-tube, substantially as described.

- 5 10. The combination with a vaporizing tube having a vapor-outlet, of a coupling arranged for attachment to a supply-pipe and carrying such vaporizing-tube, such coupling having a bore or passage and a valve-seat, a
10 valve in such coupling carrying a needle positively attached thereto to move in the same direction with said valve, said needle pene-

trating the vaporizer and controlling the vapor-outlet therein, and a rotary shaft or stem in said coupling having means engaging 15 with and actuating said valve.

In testimony whereof I have signed my name to this specification in the presence of two subscribing witnesses.

CHARLES PERILLAT.
